UNITED STATES PATENT OFFICE.

CARL F. OBERMAIER, OF YORK, PENNSYLVANIA.

DRUM.

1,114,798.

Specification of Letters Patent. Patented Oct. 27, 1914.

No Drawing.

Application filed June 26, 1911. Serial No. 635,473

To all whom it may concern:

Be it known that I, CARL F. OBERMAIER, a citizen of the United States, residing at 130 South Beaver street, in the city and county of York and State of Pennsylvania, have invented certain new and useful Improvements in Drums, of which the following is a full, clear, and exact description.

In the manufacture of rubber-insulated wires, cables, etc., for electrical purposes, the crude rubber, thoroughly washed to free it from foreign matter, is dried in a vacuum drier or in a heated drying chamber, and after the moisture is entirely eliminated the pure rubber is mixed in suitable mixing mills, with the other ingredients of the compound which is to be made. The substances which may be used, in addition to sulfur, are very numerous, and only a few need be mentioned here, for example, talc, chalk, zinc oxid, antimony sulfid, kaolin, etc. Sometimes small amounts of pitch, paraffin, or vaseline are added in order to obtain special results. When the mixing is complete the result is a homogeneous mass which becomes more or less plastic upon the application of heat. This mass can be formed into sheets by means of calender rolls and cut into strips if the wire or cable is to be insulated by means of so-called cutter machines, or the mass can be warmed up and fed into screw-presses or so-called tubing machines; the latter process delivering a seamless layer of insulating material. During this process the material becomes extremely soft on account of the heat applied in the machines and hence is very easily deformed, and in order to render the material less plastic the coated wire or cable is usually chilled by passing it through cold water tanks or cold air chambers, so that by the time the wire or cable reaches the take-up drum on which it is wound the insulating covering is hard enough to stand reasonable pressure without being flattened. The take-up drum is usually of metal because it has to be subjected to heat in the vulcanizer.

The vulcanizer is a large iron chamber or boiler large enough to contain one or more take-up drums, with a door that can easily be hermetically closed against a steam pressure of three or four atmospheres. The exposure of the goods to the steam pressure mentioned, equivalent to a temperature of from 130° to 160° C., is called "vulcaniza-

tion," and its object is to change the plastic compound into an elastic one. This change, which is a chemical one due to the small amount of sulfur present in the compound, takes place in a period of time depending upon the quality and quantity of the substances used, and upon the thickness of the layer which the heat must penetrate to effect the desired change. It is evident that the rubber compound becomes soft at the beginning of the vulcanization; and the result is that the coating becomes flattened where it is in contact with the drum. In order to overcome this defect rubber manufacturers effect the vulcanization in forms or molds whenever possible, but on account of the great lengths in which wires and cables are required the use of molds or forms becomes very expensive. Some makers incase the insulation in tin, which is effective but expensive as the tin has to be ripped off when the vulcanization is completed. A cheaper method, used mostly with compounds not of a very high grade, is to wrap the cable with tape after leaving the insulating machine. This method is used more with wires and cables insulated by so-called rotating cutters than those coated in tubing machines, as the latter deliver the material in too soft a state to permit the immediate application of the tape. The lateral pull of the rotating taping head is sufficient to deform the soft insulation. Still another quite expensive method is to provide the drum with a helical groove of the proper depth and form, in which the insulated wire or cable is wound.

I have therefore been led to devise my present invention, which has for its object to provide an improved method of forming an apparatus for supporting rubber compounds during vulcanization, particularly insulated wires, cables, and the like, in such manner as to prevent flattening or other deformation. A further object is to provide for this purpose a device which shall be not only effective but also convenient and inexpensive in practice. To these and other ends the invention consists in the novel apparatus and method for forming the same as hereinafter described, and more particularly set forth in the appended claims.

In carrying out my invention in the preferred manner I make use of a material known as "bakelite" for directly supporting for example, a rubber insulated wire.

"Bakelite" is a comparatively new substance, which, in its different forms offers the advantages of hard rubber, Japanese lacquer, celluloid and in some respects excels the properties of these products. It is a well defined chemical substance and not merely a mixture of a so-called "compound" like so many rubber, shellac, or other resinous compositions. "Bakelite", sometimes known as 10 oxybenzylmethylenglycolanhydrid, is obtained by the reaction that takes place when formaldehyde reacts upon certain phenols under proper conditions. Bakelite can be produced in various forms, the final product 15 of which is infusible and can resist a temperature of 572° F. or over. It is insoluble in all solvents and can withstand strong chemicals, oil, hot water, steam, etc. It can also be compounded with various filling materials and shaped or molded with great accuracy, to articles, of unusual strength. The 20 peculiar property of this compound (bakelite) in its different forms to harden under proper conditions has been taken advantage 25 of to adapt the same to this new use; and this fact that bakelite under proper applications and under proper conditions of heat-supply becomes a hard mass not affected by temperatures necessary to perform the process of vulcanization, offers a very suitable 30 and cheap material and is an excellent medium to support the insulating compound during the transition from a plastic to an elastic mass.

35 With the above brief digression as to the characteristics or properties of bakelite, or its equivalent, alone or in combination with suitable fillers, I will now proceed to describe its function in my new apparatus for 40 vulcanizing articles composed of or covered with rubber or rubber compounds to prevent deformation of the rubber. In the case of cords, tubing, rubber coated wires, cables, etc., a metal drum is used upon the cylindrical portion of which the bakelite is coated to a suitable depth and in this plastic material a helical groove is formed equal substantially to one-half the diameter of the cord, cable, etc., together with the insulating material thereon which are to be vulcanized thereon. When the bakelite or its 45 equivalent, is thus applied to the drum in its plastic condition and the helical groove suitably formed therein, the drum and the

55 plastic material thereon are subjected to proper heat conditions to cause the bakelite compound, together with any filling materials with which it may be desirable to use the same, such as asbestos to harden; or, as it is termed "bakelize" thereon. In other 60 words a transition takes place in the bakelite from a coherent, plastic mass to the form known as "bakelite C". This material when thus hardened, as stated above, is not affected by temperatures necessary to perform 65 the process of vulcanization, and the helical groove therein provides an admirable support for cords, tubing, coated wires, cables, etc., to support the softened or softening rubber-compound and effectually prevents deformation thereof. When the vulcanization is completed and the article removed from the vulcanizer, the same can be readily removed from the helical groove 70 and the article will be intact and in its original form. 75

What I claim is:

1. In a device for vulcanizing cables, wires and the like composed of or covered with rubber or rubber compounds, a cylindrical 80 drum, and a coating of bakelite for the cylindrical portion of the drum, having a helical groove therein to receive the cables, wires and the like.

2. In a device for vulcanizing cables, 85 wires, and the like composed of or covered with rubber or rubber compounds, a cylindrical drum, and a coating of bakelite on the cylindrical portion of the drum having a helical groove formed therein and hardened 90 while on said drum, said groove adapted to receive the cables, wires, and the like.

3. In a device for vulcanizing cables, 95 wires, and the like, composed of or covered with rubber or rubber compound, a drum, and a coat of material having a helical groove therein and hardened on said drum by heating so as to be thereafter unaffected by the vulcanizing temperature, said groove adapted to receive the cables, wires, and the like. 100

In testimony whereof I affix my signature in the presence of two subscribing witnesses.

CARL F. OBERMAIER.
